UNITED STATES PATENT OFFICE

JOHN W. STEPHENSON, OF TOLEDO, OHIO, ASSIGNOR TO THE NATIONAL MALLEABLE CASTINGS COMPANY, OF CLEVELAND, OHIO, A CORPORATION OF OHIO.

LOCKING MECHANISM.

1,122,044.

Specification of Letters Patent. Patented Dec. 22, 1914.

Application filed May 25, 1914. Serial No. 840,758.

To all whom it may concern:

Be it known that I, JOHN W. STEPHENSON, a citizen of the United States, residing at Toledo, Lucas county, Ohio, have invented new and useful Improvements in Locking Mechanism, of which the following is a specification, reference being had to the accompanying drawings, in which—

Figure 1 is an elevation showing a form 10 of my improved locking mechanism applied to a rail joint; Fig. 2 is a plan thereof partly in section; Fig. 3 is a section on lines III—III of Fig. 2; Fig. 4 is a detail of the locking or key member, and Fig. 5 illustrates various sections of the locking member shown on the lines *a*, *b*, *c*, *d* and *e* of Fig. 4.

My invention relates to locking members for relatively movable parts and consists 20 particularly in an improvement on the locking or key member described and claimed in my reissued Letters Patent No. 13,570, dated June 3, 1913. I have found, in practice, that where the bendable key is driven into 25 the receiving slot, sometimes, by reason of the clearance necessarily permitted in such slot, variations in the size of the keys or in the size of the slots will permit the key to be drawn back slightly after being 30 driven to locking position, so that looseness will occur between the wedge and the shoulder of the key, which may result in the device becoming ineffective.

My present invention consists in forming 35 the slot in such manner that, regardless of variations in the sizes of the slots or in the key, the key will be locked in any position to which it is driven. To this end I prefer to form the slot with curved or inclined 40 faces so that the metal of the key when driven will be distorted or bent with relation to its central axis and will thereby be held firmly and positively in any position to which it may be driven.

45 Referring to the drawings in which I have shown my invention as applied to a rail joint, *A* indicates the rail, *B* the fastener plate, *C* the wedge members, *D* the locking or key member, and *E* a rail engaging member. The rail engaging member *E* has a slot 2, which contains a hump or boss 3, which is so arranged that the central por-

tion of the key *D*, when applied, will be driven in and bent into concave form over the hump, and will thereafter be bent in 55 flattened form by the usual curved portion 4 of the slot in the entering end. The key or locking member, prior to application, is of the usual flat form, and when driven home will assume the shape shown in Figs. 60 2, 3, 4 and 5, in which its end portion 5 is bent upon the curved portion 4 of the slot, and its central portion 6 is bent over the hump or boss 3. The key *D* has the usual head 7, which bears against the rear face 8 65 of the wedge *C*, to hold the wedge in wedging position against the rail engaging member *E*.

It will be seen that as the bendable locking member is driven home in the slot it 70 will immediately become locked and that there will be no slack which will permit the wedging members to become loose. It will also be seen that various modifications may be made in the construction which I have 75 described and shown without departing from my invention.

What I claim is:

1. In a locking device for relatively movable parts, a key member having a shoulder 80 and a bendable portion, a channel adapted to receive the bendable portion of said key, successive cross sections of said channel being of different shapes, whereby a cross section of the key member is distorted, when 85 driven into engagement with the walls of the channel.

2. In a locking mechanism for relatively movable members, a plurality of wedge members adapted to be moved relatively to 90 each other longitudinally into wedging engagement to clamp a third member, one of said members containing a deflecting channel and a separate bendable key member arranged to be driven longitudinally of the 95 relatively movable members and into said deflecting channel to hold the wedge members in wedging position, the said key member in driven position having cross sections of different shape from the original cross 100 section.

3. In a track fastener, a plurality of wedging members adapted to be moved relatively to each other longitudinally of the

rail into wedging engagement with each other to clamp the rail, one of said members containing a deflecting channel and a separate key member adapted to be driven into said channel to hold one of said wedging members in wedging position and being in driven position bent at different portions in

its length out of coincidence with its original cross sectional shape.

JOHN W. STEPHENSON.
